UNITED STATES PATENT OFFICE.

ARTHUR WEST, OF MANITOU SPRINGS, COLORADO.

DESIGN FOR A SPOON, &c.

SPECIFICATION forming part of Design No. 20,960, dated July 21, 1891.

Application filed June 26, 1891. Serial No. 397,654. Term of patent 7 years.

To all whom it may concern:

Be it known that I, ARTHUR WEST, a citizen of the United States, and a resident of Manitou Springs, in the county of El Paso, 5 State of Colorado, have invented and produced a new and Original Design for Spoons, Forks, Knives, &c., of which the following is a specification.

The leading feature in my design consists 10 in the representation of a loaded "burro" or ass standing across a railroad-track on the handle of the article and the representation of a balanced rock on the bowl portion thereof.

In order that my invention may be fully 15 understood, I will proceed to describe it with reference to the accompanying drawing, which is a front elevation showing my design for a spoon.

1 is the handle, 2 is the bowl, (or solid por-

tion in a fork or the blade of a knife,) and 3 20 is the shank connecting the handle with the bowl. On the handle I show a railroad-track 4, across which stands a loaded burro or ass 5, and on the bowl is the representation of a rocky surface 6 and a balanced rock 7. Between the handle and the bowl in the shank is a space 8 for lettering. In this space I have placed the word "Manitou."

Having thus described my invention, the following is what I claim as new therein and 30 desire to secure by Letters Patent:

The design for spoons, forks, knives, &c., substantially as herein shown and described.

ARTHUR WEST.
